CLAIM

The ornamental design for a housing for a network device, as
shown and described.

DESCRIPTION

FIG. 1 is a perspective view of an embodiment of a housing
for a network device showing our new design, as viewed from
the top and one side.

FIG. 2 is a front view of the housing shown in FIG. 1.

FIG. 3 is a back view of the housing shown in FIG. 1.

FIG. 4 is a first side view of the housing shown in FIG. 1.

FIG. 5 is a second side view of the housing shown in FIG. 1.

FIG. 6 is a plan view of the housing shown in FIG. 1; and,
FIG. 7 is an inverted plan view of the housing shown in FIG.

1.

The details shown in broken lines illustrate portions of the
housing for a network device that form no part of the claimed
design.
